(54) STRAW CUTTER

(76) Inventor: **Stephen Ustick**

Stephen Ulstick
Patent for a Straw cutter

The Schedule referred to in these Letters Patent, and making part of the same, containing a description in the words of the said Stephen Ulstick himself, of his improvement in his Straw cutter, for which he obtained from the United States Letters Patent bearing date October 3, 1834.

To all to whom these Presents shall come

Be it Known, that I, Stephen Ulstick of Philadelphia, in the county of Philadelphia, and State of Pennsylvania, have invented a new and useful improvement in the Straw cutter, for which I obtained Letters Patent, from the United States, bearing date October 3, 1834, a Schedule of which is given below, and that the specification ~~generally~~ succeeding said Schedule, is a full and exact description of the construction and operation of the said improvement as invented by me:

Schedule referred to above - To all to whom these Presents shall come, Be it Known, that I, Stephen Ulstick of Philadelphia, in the county of Philadelphia, and State of Pennsylvania, have invented a new and useful improvement in the Straw cutter, for cutting straw, hay, & corn stalks, called Stephen Ulstick's Straw Cutter, and that the following is a full and exact description of the construction and operation of the said machine as invented by me -

In the first place I have a frame constructed as follows - two posts, which I call the front trough posts, are framed into a base, one foot apart and said base extends beyond the right hand post, and has a post, which I call the first crank post, framed into it 6 inches from said post, the first crank post is framed at top into one end of a nail, which is framed at the other end into the right hand trough post above specified. This nail serves as a foundation for a

and upon back of the crank which is described below. The other judgment box of the crank rests on the cap of a post, which I call the second crank post, which is in front of the first one, and connected with it by 2 rails, one near the bottom of the posts, and the other so far below the top, as to allow the crank below specified, to work above it. There are 2 posts which I call the back trough posts, framed into a base of the same distance apart as the front trough posts, and are connected above by a rail, on which the back end of the bottom of the trough is nailed. The back trough posts are framed below on one end of two rails which are framed at their other end into the front trough posts at one end, and nailed at their other end, on the inside edges of the back trough posts, the said posts being cut out the thickness of the sides to receive them. The bottom of the trough is in a horizontal position lengthwise, the right hand edge is one inch lower than the left hand one, it extends from the back of the trough to a fluted cast iron feed roller in front, whose judgment turns in the sides of the trough, just behind the trough posts. This top of said roller extends 1. inch above the bottom of the trough. The sides of the trough are tapered from the said feed roller to their back end to make the trough wider behind than before. This trough is only $\frac{3}{4}$ feet long. I extend the trough 2 ft 6 inches further, by having a separate trough to fit at front, to its back and fasten it thereto, by having ^{steps} iron fastened on the top edges, at front which extend over the tops of the back trough posts and fit by means of holes in their front ends on iron pins, which are permanent in the ends of the posts, and by strips nailed on the back of the first trough, at the sides and bottom. The trough is made in two pieces, as described above, for the purpose of this back part being taken off when the machine is not in use, so that the machine may then take up but little room.

There is an opposing edge fastened on the mouth of the trough.

by means of screws, it consists of a bottom of uprights standing around the uprights. The top of the bottom part of said edge ranges with the top of the feed roller above specified and is of the same height. There is a strip of iron extending from it to the roller in a descending position which serves to guide the straw in front of the roller over the opposing edge. There is another feed roller like the above over it. It is in a horizontal position, lengthwise, and its guides work in a frame whose uprights work between the front-brushposts and strips, which are fastened to the sides of the trough. The uprights have a nail at top above the roller, and one at bottom which is near the bottom side rails. There are two springs, one to each side of the said frame, which are fastened at one end, to the bottom side rails of the machine, the other ends bear on the bottom rail of the roller frame. They are to incline the upper roller towards the lower one, to compress the straw.

There is a cast iron frame with a short tongue at each corner. The tongues slide in cast iron grooves inserted in edges of two rails, which are fastened on the front of the machine, by means of screws or bolts. Said rails are in an oblique position, and may be more or less oblique, running downward from the right side of the machine. There is a knife at the backside of said frame in such a position with it as to be parallel with the top feed roller. The back edge of it comes against shoulders of the frame, each end at the bivelure seats on two screws which run through the frame. There is one screw at each end of the knife, in a counterbore position with the above and between them. The heads of these are countersunk in the face of the knife, they have tops on their tail ends, which bear against the face of the frame. The use of the first described screws is to regulate the set of the knife. The knife frame vibrates by means of a crank and Peterman. The Peterman is connected with the frame by a pivot which is fastened in the lower corner of the latter. There is a balance wheel on the front end of the crank, which has a handle on one of its arms by which the crank is turned. In the downward

motion of the knife frame, the knife cuts the straw, when it has nearly returned, the straw is fed by means of a slope knob of the lower end of the frame working against the front end of the horizontal shaft, which works on bushes that are secured to the trough posts of that side of the machine; there being a catch hung on the inside of said shaft, which operates on a ratchet wheel of the bottom roller and one hung to an upright of said shaft operates on a ratchet wheel of the top roller. The upper catch is above its ratchet wheel, the lower one is below its ratchet wheel; it is kept up against the ratchet wheel by its tail end being heavier than its bill part. The top roller is kept from turning backwards, by means of two palls hung on the upright of the roller frame, operating on the ratchet wheel. The bottom roller is kept from turning backwards, by two palls hung on the quieting strip of the roller frame at that side of the machine. The upright of the roller frame has a slot in it, which works over the jaw gear of the bottom roller on which the ratchet wheel is. As the knife goes down, the catch-shaft above described slips forwards by means of a half circle spring, whose tail bears against the bushes of the catch-shaft. The feed of the roller is regulated by a flat head screw in the back end of the catch-shaft, which slides in the hole of the plate fastened on the trough posts. The head of said screw coming against the plate prevents the catch-shaft above described being pushed too far forward by the spring described above.

There is a board, with the grain of the wood running front and back, fastened to the upper end of the roller frame above described, in front of the upper roller, extending between 10 and 12 inches in height of the bottom of the roller. Its face is nearly as far in front as the opposing edge. The use of it is to prevent the straw from being raised by the knife in the upward motion.

(By the position of the knife and the opposing edge with the rollers, and the direction of the knife frame as described above I get a much greater draw of the knife on the straw, than can

otherwise be obtained with a crank of equal length, which makes it out much easier.

What I claim as my invention, is the arrangement of the bottom of the trough, the opposing edges the feed rollers, the position of the knife and the direction of the knife frame collectively and the general construction of the Machine as described above.

In testimony, that the above is my invention, I have hereunto affixed my hand this nineteenth day of September, in the year of our Lord, One thousand, eight hundred and thirty four.

The improvement for which a patent is desired, consists in apparatus for feeding and carrying, being the same in view of that described in the above Schedule, as which is of the following construction:

There is a groove in each side of the front trough, within one inch of the bottom edge, the top edge of which is even with the, passing edge. The bottom of the trough consists of three pieces of board, the grain of which runs cross-wise of it in said groove. The first of said pieces is 6 1/2 inches wide, the second which I call the lower feeder 8 inches, and the third commences within 9 1/2 inches of the first and extends to the back of the trough. The first and third are straight, but the second one, or lower feeder is bent backward, and forward in the grooves described above, as described below.

There is a piece of sheetiron screwed on the front of said feeder, at the front edge, which extends over the back edge of the first piece of bottom; and there is a similar piece fastened in the same manner to the third piece, which extends over the back edge of the feeder. They are to break the spines in front and back of the feeder, to prevent the straw from catching therein as it vibrates.

There is a perpendicular frame, whose base is mounted on blocks,

on the lower side of the above specified feeder, and whose uprights are outside of the trough sides, and which extend one foot above them, in each of which there is a groove extending from $\frac{1}{2}$ of an inch of the side upwards. The upper rail of the frame is framed behind said groove. There is a board which I call the upper feeder, one foot wide, whose ends for 5 in. from its upper edge slide in said groove. The lower part of the ends is cut out, to allow the feeder to descend in the trough. There is a box on the face of said feeder, which holds sand, or gravel, to compress the straw between it and the lower feeder. The feeder forms one side of the box. *

There is a square frame, which I call the compreiser, whose uprights have tongues on them, which slide in grooves of the front trough posts. Said tongues extend below the bottom rail of the compreiser, and through the ends of the front pieces of trough bottom, so that as the compreiser is elevated, as is described below, the grooves below the lower rail of it are still filled, to prevent straw from working in them. The face of the compreiser is flush with the face of the posts. The bottom rail of it, 6 $\frac{1}{2}$ inches deep and 3 inches thick, it extends at the ends over the uprights between the posts. -

There is a strip of cast iron $1\frac{1}{2}$ inches wide, with edges on its face formed by square edges in front and blunt ones back-wards, therefore inserted in the face of the lower feeder at its front and a similar one, one inch wide, screwed on the lower edge of the upper feeder.

There is a cast iron wheel with a groove on each side near its periphery, which fits eccentrically on the square of the tail end of the crank specified in the above schedule, which is to be of lever

which is hung on a pin in the back side of the second trough post, a. on the trough. The lever is connected with the wheel by means of pins, four of which are on the sides of the former, working in the grooves of the latter. As the knife is elevated, the compreeler is also elevated, by means of its being coupled with the above specified lever, by a shaft, which works on a pin in the back of the lower rail of the former, a. bone through a perpendicular mortise of the latter, there being a slot in the upper end of the shaft to prevent the lever from giving the compreeler a downward motion, but which is given to it by a spring which bears on the upper end of a shaft which passes through a cap rail of the front trough posts, and bears with its lower end in a mortise of the top rail of the compreeler. The ends of the shaft are rounded to allow it to shift its position, to suit the changes of the spring. The upper end is rounded each way, and the spring has a counterbore to prevent its slipping off. The heel of the spring is screwed to the cap rail. As the compreeler descends, the upper feeder ascends by means of a chain being attached at one end to it, and hung on a pulley in an arm from the cap rail, above specified, and attached at the other end to the lever. Then the compreeler is up, the feeders are moved forward, and thus push the straw forward and ^{down} as they are pushed back again, for another action on the straw, by an upright of a crank, ^{up} in a mortise of the front end of an arm, which is soldered on the lower side of the lower feeder. The work works in holes which are screwed on the side rails of the straw line. There is a end of the crank which extends towards the front of the machine, the extremity crooked upward, and which bears with a horizontal lever, which works on a pivot in the outside edge of the back trough post. The handle of this lever is operated upon by the hand described. The lever is hung connected therewith by means of an upright bar, ^{up} whose ends are in mortises of the levers in pins, through the back of the machine, the upper end of the said shaft has a slot

in it, in which the point of the lower slides until it has nearly got to each extreme point.

There is a slot through the base of the frame in which the upper feeder slides, with its tail end against the upright of the feeder crank, the turning of which gives more or less motion to the feeders, as may be required. The hole in the plate in which the upright works being long enough to allow some play of the latter.

* Instead of the said feeder and frame, there may be a square frame, with its slides clicking against the blocks on the outside of the troughsides, at each edge the bottom rail is below, and the top rail above the trough, and a saddle, which fits inside of the troughs with its top fast to the lower edge of the top rail of said frame. There is a strip, as in Fig. 3 and 3a, and is fastened to the lower side of the lower feeder, this being blocks on the former to hang at below the trough. There are uprights, as in the ends of said strip, in which the slides of the frame abut. The frame is kept in a perpendicular position by the strip, one each side of the lower rail and frame into the strip described above, and near the upright of the feeder crank. The regulator is fast in the strip as in Fig. 3 of the drawing of the upper feeder first described.

What I claim is, my新颖 device, in the shape of a bottom denominator of the invention, and the general construction of the feeding apparatus, as herein described.

In testimony that I have on my invention I have hereunto affixed my hand this 21 day of January, in the year of our Lord One thousand eight hundred and thirty five.
